UNITED STATES PATENT OFFICE.

JOSEPH I. C. CLARKE, OF NEW YORK, N. Y., ASSIGNOR OF TWO-THIRDS TO FERDINAND WESEL AND DAVID M. OVIATT, OF SAME PLACE.

INTERCHANGEABLE PLATE FOR STEREOTYPE-FORMS.

SPECIFICATION forming part of Letters Patent No. 415,615, dated November 19, 1889.

Application filed July 24, 1888. Serial No. 280,860. (No model.)

To all whom it may concern:

Be it known that I, JOSEPH I. C. CLARKE, of the city, county, and State of New York, have invented certain new and useful Improvements in Interchangeable Plates for Stereotype-Forms, of which the following is a specification.

This invention relates to stereotype-plates having interchangeable name or edition plates, whereby different editions of the same paper can be quickly printed from the same stereotype-plate.

The object of the invention is to provide a simple means for holding the edition or name plate and facilitating its exchange.

In the accompanying drawings, Figure 1 represents a form with a page of a newspaper locked in the same, showing the type-high dummy. Fig. 2 is a side view of one of the side gages used in the mold for casting the stereotype-plate, showing a projection on the side of the gage. Fig. 3 is a vertical transverse section of a mold for casting the stereotype-plate, showing the side gages, either of which may be furnished with a projection for making a recess in the plate. Fig. 4 is a perspective view of a stereotyped page-plate ready to be placed in the press, showing the recess. Fig. 5 is a detail front view of the detachable name or edition plate used in connection with the stereotype-plate; and Figs. 6 and 7 are respectively a vertical transverse section on line $x-x$, Fig. 7, and a front view of the stereotype-plate with interchangeable name or edition plate, drawn on a larger scale and illustrating, in connection with Figs. 1 and 4, my improved method of making stereotype printing-plates with interchangeable name or edition plates.

Similar letters of reference indicate corresponding parts.

In carrying out my invention, the front or other page of a newspaper which is to be printed in several editions is set up and locked in a form in the usual manner, it being provided at the head or other suitable point with a type-high piece or dummy b , so as to produce thereby an impression in

the pulp-matrix made from the form and a recess b' of corresponding size in the stereotype-plate cast from the same. The pulp-matrix is next made from the front page, the dummy making an impression at the point where the change in the stereotype-plate is to be made. The matrix is then transferred to a mold of the usual construction and retained by side gages d , Figs. 2 and 3, one or both side gages being provided with a projection d' , which corresponds in size and shape with the impression made in the matrix by the dummy b . The stereotype-plate is then cast in the mold, the recess b' being formed at that point where the projection d' of the side gage d is located, said recess serving for receiving the interchangeable name or edition plate N , as shown in Fig. 5.

The name or edition plate N is provided with a shank n , which is retained by the margin-bar E on the type-cylinder, as shown in Figs. 6 and 7. The margin-bar E is provided with a recess e , which corresponds to the size of the shank n of the plate N . When an edition is printed, the plate N is removed and another plate N , representing the second or other edition plate, is inserted and secured on the type-cylinder by the margin-bar. Suitable fasteners—such as screws—serve to secure the margin-bar E to the type-cylinder. The next edition is then printed and afterward the name or edition plate changed again, another edition printed, and so on, as many changes being made in the plates at the heading or other suitable point of the page as editions or issues are required.

My improved means for changing the name or edition plate on the stereotype-plate of the type-cylinder facilitates the issuing of the several editions, as it saves time and expense in getting them ready, which is of the greatest importance in the newspaper business.

Having thus described my invention, I claim as new and desire to secure by Letters Patent—

The combination of an impression-cylinder, a stereotype-plate having a recess, a

changeable name or edition plate having a laterally-extending shank of less thickness than the body of the changeable plate, a margin-bar for holding said changeable plate, 5 provided with a recess adapted to receive said shank, and fasteners for securing said bar to said cylinder.

In testimony that I claim the foregoing as my invention I have signed my name in presence of two subscribing witnesses.

JOSEPH I. C. CLARKE.
